UNITED STATES PATENT OFFICE.

SATTERLEE ARNOLD, OF MORRISTOWN, NEW JERSEY, ASSIGNOR TO ANNA M. ARNOLD, OF SAME PLACE.

THREAD-CONTROLLING MECHANISM FOR SEWING-MACHINES.

SPECIFICATION forming part of Letters Patent No. 391,352, dated October 16, 1883.

Application filed December 12, 1887. Serial No. 257,666. (No model.)

To all whom it may concern:

Be it known that I, SATTERLEE ARNOLD, a citizen of the United States, residing at Morristown, in the county of Morris and State of New Jersey, have invented certain new and useful Improvements in Thread-Controlling Mechanisms for Sewing-Machines, of which the following is a specification, reference being had therein to the accompanying drawings.

10 My invention relates to an improved automatic device for feeding a measured quantity of needle-thread for each stitch made by the stitch-forming mechanism of a sewing-machine.

15 In the thread feeding or measuring pull-off devices heretofore in use, in which the thread was clamped by an intermittent tension arranged to act on the thread between the pull-off and the needle when the pull-off was operating, certain objections have arisen by reason of the fact that the clamping or intermittent tension was placed so far from the pull-off that the elasticity of the long stretch of thread between the pull-off and clamping-tension (particularly when sewing with silk thread) was so great that the action of the pull-off was rendered uncertain, and the thread could not therefore be fed to the needle with the accuracy desired. These defects are remedied by my invention, which includes two intermittently-operating thread-clamps alternately actuated, so that the thread is always held between one or the other. One of the said clamps prevents strain on the thread running from the pull-off to the take-up and needle when the pull-off is operating, and the other prevents the thread from being drawn from the spool or other source of supply when the take-up is tightening a stitch. These intermittent thread-clamps are preferably both placed adjacent to each other and to the pull-off, so that they can be operated by a single moving part, and so that there will not be any considerable length of thread between the

35 measuring pull-off and the clamp which holds the thread when said pull-off is operating. My measuring pull-off, in connection with the intermittent thread-clamps, thus constitutes a reliable and accurate thread-feed capable of 40 adjustment to such a nicety that the exact

quantity of thread desired can always be uniformly supplied to the needle.

In carrying my invention into effect I prefer to mount the pull-off, the co-operating thread-clamps, and the operating device or lever on a base-plate or support, which may be attached to the arm or any other suitable portion of the machine, the operating-lever being arranged to be actuated by the needle-lever or other moving part of the machine.

To enable those skilled in the art to which my invention relates to fully understand the same, I will now describe the construction and operation thereof in connection with the accompanying drawings, in which—

Figure 1 is a side view of the upper part of a sewing-machine with my invention applied thereto. Fig. 2 is a detail perspective view of the pull-off and clamping devices and the base-plate on which they are mounted. Fig. 3 is a plan view of the same. Fig. 4 is a longitudinal sectional view of Fig. 3. Fig. 5 is a cross-section on line 5 5, Fig. 3. Figs. 6 and 7 are detail plan views of the upper and lower clamping-plates, and Fig. 8 is a detail plan view of the operating-lever.

In the machine herein shown the arm A, the vertical driving-shaft B, having near its upper end an eccentric connected by a pitman, C, to a primary needle-operating lever, D, the link d, the secondary needle-operating lever E, the link d', and the needle-bar F are or may be essentially the same as in my patent, No. 331,106, dated November 24, 1885.

The take-up mechanism herein shown, and consisting of the take-up levers G, connected with the cam g on the shaft B, through the rocker g', pitman g'', and link g'', is embraced by my application, Serial No. 257,667, filed simultaneously herewith, and is not herein claimed; but instead of this particular take-up mechanism it will be understood that any other well-known or suitable take-up may be employed in connection with my thread feeding and clamping devices.

Secured to the arm A is the thread-feed base-plate H, having the upwardly-projecting lugs h and h'.

I is an operating-lever pivoted to the base-plate at i and having side projections or

wings, i^2 , provided with beveled edges i' . The said lever is also provided at its free end with a slot, i^3 , for the reception of an operating-pin, d^2 , carried by the lever E.

5 M is the lower clamping-plate, of thin spring metal, and K is the upper or rigid clamping-plate. The arms m and m' of the plate M are bent slightly, so that they normally spring away from the arms k and k' of the plate K, 10 these clamping-arms being forced together by the wings i^2 of the lever I, the beveled edges of the said wings sliding under the said arms m and m' and forcing them into clamping contact with the arms of the plate K as the said 15 lever is vibrated back and forth, these parts being so arranged that the clamp composed of the arms m and k will be closed just as the clamp composed of the arms m' and k' is opened, and thus the thread passing between 20 these clamping-arms will always be positively clamped by one clamp or the other.

The plate M is raised above the base-plate H a distance equal to or slightly greater than the thickness of the lever I by the plate J, 25 and both of these plates may be riveted or otherwise permanently secured to the said base-plate. The arms of the plates M and K are provided with thread-escape notches m^2 and k^2 , and the latter plate is pivotally attached to the 30 base-plate H by a screw, k^3 , beneath the head of which is a spring washer, k^4 , which, while reliably holding the said plate K in operative position, permits the said plate to be swung aside, as indicated by dotted lines in Fig. 3, to bring 35 the escape-notches of the said plates opposite each other, and thereby permit the thread to be drawn freely through the clamps when desired. The plate K is provided with a pin, k^5 , by which it may be thus conveniently 40 swung aside or returned to its operative position.

The lever I is provided with a pull-off pin, i^4 , operating in connection with a loop or arch, n , of an adjustable resistance-plate, N, secured 45 by a screw to the lug h of the base-plate, the said loop or arch being of proper height to permit the said pin to pass under it and draw a bight of thread passing around one of the uprights of the arch through the latter, as 50 shown in Fig. 3. The free end of the plate N may be adjusted to any desired position by the regulating-screw n' , passing through the lug h' of the base-plate and furnished with a set-nut, by which it may be secured in place 55 after adjustment. As the lever I has a uniform movement, it will be apparent that when the plate N is adjusted toward the lug h' a shorter bight of thread will be drawn through the arch n by the pin i^4 ; but when the said 60 plate is adjusted away from the said lug a longer bight of thread will be drawn through the said arch from the thread-spool. The said plate N, which is of spring metal, is bent slightly, so that it remains in contact with the 65 regulating-screw n' , whatever its position of adjustment.

The plate H is preferably provided with guard-pins h^2 to prevent the thread from escaping from between the clamping-arms.

For convenience of description the clamp 70 consisting of the arms k and m of the plates K and M may be termed the "pull-off clamp," as it holds the thread from being drawn backward from the take-up and needle while the pull-off is operating, and the clamp consisting 75 of the arms k' and m' of the said plates may be termed the "take-up clamp," as it holds the thread from being drawn from the spool when the take-up is tightening the stitches.

When in the operation of the machine the 80 lever I is moved toward the left, Fig. 3, the thread will be firmly held between the clamping-arms k and m , and the pull-off pin i^4 , passing under the arch n of the resisting-plate N, will then draw the required quantity of thread 85 from the spool for the stitch which is to be made. As the said lever swings to the right the pull-off clamp, consisting of the arms k and m opens, and the take-up clamp consisting 90 of the arms k' and m' is at the same instant closed, leaving the loop just drawn from the spool free to be fed to the needle, the said take-up clamp holding the thread firmly while the stitch is being tightened.

The above-described intermittently-operating or automatic take-up and pull-off thread clamps are not tension devices in the sense that they exert an appreciable tension or drag on the thread, excepting when they clamp or hold the same positively or when they are in 100 clamping operation, the said clamps opening when permitted to do so by the removal of the wings of the lever I to allow the thread to pass freely; but as the thread is always held positively by one or the other of the clamps 105 it will be readily understood that no tension on the thread other than this positive holding will be necessary.

My improved thread-feeding mechanism is specially designed for use in sewing elastic 110 seams of lock-stitches in knit goods and other similar elastic fabrics, and practical use of the same has demonstrated that by its assistance the elasticity of the seams may be regulated with the greatest exactness, producing results 115 heretofore unattainable with lock-stitch machines.

It will of course be understood that my clamping thread-feeding mechanism may be used with other forms of machines than that 120 herein shown, and with or without a take-up; also, that my improved pull-off may be used in connection with either one or two thread-clamps or with ordinary intermittent tension devices, if desired. It will also be understood 125 that the details of my invention may be varied within the province of mechanical skill without departing from the spirit of my invention.

I claim—

1. In a sewing-machine, the combination, 130 with a pull-off, of a thread-clamp located to act on the thread between the said pull-off and

- the thread source or supply, a second thread-clamp located to act on the thread between the said pull-off and the needle, and positively-actuated means for alternately operating the 5 said thread-clamps.
2. In a sewing-machine, the combination, with a pull-off, of a thread-clamp located to act on the thread between the said pull-off and the thread-supply, a second thread-clamp located to act on the thread between the said pull-off and the needle, and a single positively-actuated device for alternately operating the 10 said clamps.
3. In a sewing-machine, the combination, 15 with a pull-off, of an intermittent tension or thread-clamping device placed closely adjacent to the said pull-off and arranged to clamp the thread between the pull-off and the needle, whereby only a short portion of thread will 20 extend between the pull-off and clamp and unreliable action due to stretching the thread will be avoided.
4. The combination, with a sewing-machine thread-feeding device consisting of a pull-off, 25 a thread-clamp located to act on the thread between the said pull-off and the thread-supply, and a second thread-clamp located to act on the thread between the said pull-off and the needle, said pull-off being provided with 30 means for alternately operating the said thread-clamps, of a single base plate or support which is separate from or independent of the frame of the sewing-machine and on which the said pull-off and thread-clamps are all mounted, 35 whereby the said feeding device is adapted to be attached to any suitable part of an organized sewing-machine.
5. The combination, with the pull-off and the upper and lower clamping-plates, each 40 having two clamping-arms provided with thread-escape notches, said pull-off being arranged between the clamping-arms of said plate, of a base plate or support to which one of the said clamping-plates is fixed and with 45 which the other is pivotally connected, so that it may be swung aside for a free passage of the thread through both clamps.
6. The combination, with the base-plate and the upper and lower clamping-plates, each having two clamping-arms, of an operating-lever arranged between two sets of arms and provided on its opposite sides with wings or 50 projections for alternately closing the two clamps consisting of the said clamping-arms.
7. A sewing-machine pull-off consisting of 55 the adjustable resistance-plate, N, having the loop or arch n , and the swinging lever I, having the pull-off pin i^4 , arranged to travel through the said loop or arch.
8. The combination, with a pull-off device 60 consisting of a stationary but adjustable resistance-plate having a loop or arch to form an opening, of a lever having a pull-off pin to travel through the said opening and two 65 thread-clamps, one on each side of the said pull-off, alternately operated by said lever.
9. In a sewing-machine, the combination, 70 with a take-up and a pull-off, of an intermittently-operating thread-clamping device or take-up clamp arranged to act on the thread between the said pull-off and the spool or other source of supply of the thread, and a second 75 intermittently-operating thread-clamping device or pull-off clamp arranged to act on the thread between the said pull-off and the said take-up, and positively-actuated means for alternately operating said thread-clamping devices.
10. The combination, with the base-plate H, 80 of the plates K and M, each having two clamping-arms, the operating-lever I, having a pull-off pin, i^4 , and two wings provided with beveled edges, and the adjustable resistance-plate N, having the arch or loop n , under which the said pull-off pin travels.

In testimony whereof I affix my signature in presence of two witnesses.

SATTERLEE ARNOLD.
